CLAIM

The ornamental design for a phone case, as shown and described.

DESCRIPTION

FIG. 1 is a top perspective view showing the top, front, and right sides as well as the inner left interior surface of a first embodiment of a phone case;

FIG. 2 is a bottom perspective view showing the bottom, front, and left sides as well as the inner right interior surface of the first embodiment of the phone case;

FIG. 3 is a further bottom perspective view showing the bottom, front, and right sides as well as the inner left interior surface of the first embodiment of the phone case;

FIG. 4 is a further bottom perspective view showing the bottom, left, and rear sides of the first embodiment of the phone case;

FIG. 5 is a front elevation view of the first embodiment of the phone case;

FIG. 6 is a rear elevation view of the first embodiment of the phone case;

FIG. 7 is a left side elevation view of the first embodiment of the phone case;

FIG. 8 is a right side elevation view of the first embodiment of the phone case;

FIG. 9 is a top plan view of the first embodiment of the phone case;

FIG. 10 is a bottom plan view of the first embodiment of the phone case;

FIG. 11 is a top perspective view showing the top, front, and right sides as well as the inner left interior surface of a second embodiment of the phone case;

FIG. 12 is a bottom perspective view showing the bottom, front, and left sides as well as the inner right interior surface of the second embodiment of the phone case;

FIG. 13 is a further bottom perspective view showing the bottom, front, and right sides as well as the inner left interior surface of the second embodiment of the phone case;

FIG. 14 is a further bottom perspective view showing the bottom, left, and rear sides of the second embodiment of the phone case;

FIG. 15 is a front elevation view of the second embodiment of the phone case;

FIG. 16 is a rear elevation view of the second embodiment of the phone case;

FIG. 17 is a left side elevation view of the second embodiment of the phone case;

(Continued)

FIG. 18 is a right side elevation view of the second embodiment of the phone case;
 FIG. 19 is a top plan view of the second embodiment of the phone case; and,
 FIG. 20 is a bottom plan view of the second embodiment of the phone case.
 The broken lines in the drawings represent portions of the phone case that form no part of the claimed design.
